UNITED STATES PATENT OFFICE.

FRANK L. CROCKETT, OF NORTH UXBRIDGE, MASSACHUSETTS, ASSIGNOR TO THE WHITIN MACHINE WORKS, OF WHITINSVILLE, MASSACHUSETTS, A CORPORATION OF MASSACHUSETTS.

COMBER-CASING.

1,272,013.

Specification of Letters Patent.

Patented July 9, 1918.

Application filed December 10, 1915. Serial No. 66,049.

To all whom it may concern:

Be it known that I, FRANK L. CROCKETT, a citizen of the United States, residing at North Uxbridge, in the county of Worcester 5 and State of Massachusetts, have invented the following - described Improvements in Comber-Casings.

The improvements concern the inclosure of the comb cylinder and scavenging apparatus of combing machines and the combination thereof with the parts of the combing mechanism whereby the machine is adapted to confine the lint and fly generated by the combing process so as to prevent its 10 collection on exterior parts and journals and thereby avoid the necessity of frequent stoppages for cleaning. With combers as at present and heretofore constructed it is necessary to turn off the power and remove 15 the accumulations of fly and lint some two or three times each day, in order that such waste material may not contaminate the combed sliver; by the improved means herein disclosed a cotton comber, for example, 20 be kept in a clean and safe running condition for long periods, and the avoidance of the idle periods results in a material increase of productiveness as well as also in a saving of labor. The principle of the 25 invention and the best mode in which it has thus far been embodied are illustrated in the accompanying drawings, in which—

Figure 1 is a cross section through one of the heads of a well known type of multiple 30 combing-head cotton comber;

Fig. 2 a perspective of the inclosure or casing itself with parts broken away; and

Fig. 3 a sectional detail of packing clamp.

The several parts of the comber shown in 40 Fig. 1 comprise the feed plate 1, on which the lap advances to the feed rolls 2; the nipper mechanism 3 which receives and holds the forward end of the lap for engagement by the needles of the comb cylinder; the 45 detaching roll 4 which coöperates with the detaching segment 5 to detach the tuft; the top comb 7; the piecing rolls 8 which receive and piece the detached and combed tufts, producing a continuous sliver thereof, 50 and the sliver pan 9 which receives said sliver. The piecing rolls 8 may be understood to have an alternate forward and backward motion to effect the piecing action, and in the mechanism shown they are

free of contact with the detaching segment 55 5, which however engages the detaching roll on each revolution. The combing cylinder which comprises the needle half-lap and the detaching segment 5 is carried on a main or comb shaft 6, which is common to 60 all the combing heads of the machine, being journaled between each head, on intermediate frame uprights 10, mounted on a main table girder 11, according to usual design. The forward piecing roll as well as also the 65 lower feed roll are similarly formed on shafts which are common to all the combing heads and journaled in these same uprights as will be understood by those skilled in the art. The bracket arms 12, secured to the 70 rear upper ends of the intermediate frame uprights, form the supports for the springs which press the two feed rolls 2 together, and they also serve to support the casing as presently described. The nipper knife is 75 operated by the usual nipper rods 13 from the main nipper shaft 14, also journaled in the intermediate frame uprights. The sliver pan 9 is carried on brackets 15, clamped to a rod 16 fixed in the series of frame 80 uprights, and the nipper mechanism and top comb are likewise carried on the upper margins of the same uprights. The rotary cylindrical brush 17, rotating in the direction indicated, cleans the comb cylinder, as 85 usual, and is itself cleaned by the card-clothed doffing cylinder 18, and the latter is stripped of its accumulated waste by the oscillating doffer comb 19 carried on the doffer shaft 20. The doffer cylinder shaft 90 is likewise journaled in the intermediate uprights and the doffer comb shaft 20 is journaled in brackets 21 projecting in rear thereof. The various shaft journals of the machine are thus all disposed upon, or in the 95 planes of, the frame uprights, and the working parts, that is to say, the comb-cylinder, brush and doffing cylinders, occupy the intermediate spaces, all as common in this class of machine. For further explanation 100 of the said common construction, reference may be made to Patent No. 822,479, but it will be understood that the invention is not confined to any particular comber construction and may be employed on single or multiple-head machines with equal results.

The new type of casing or closure is effective for the purposes above indicated,

principally by virtue of its end wall construction which forms a screen or barrier between the rotating comb and scavenger cylinders and the various journal seats on the frame uprights, and thereby prevents air circulation in this region of the machine, such as would tend to deposit fly on the machine parts. The front and rear walls also coöperate to the same end and are specially 10 designed for the purpose, being at the same time arranged to be readily removable.

Referring to the said casing, its front wall is constituted by a sheet 22 of tin or other material, extending imperforate from 15 a point closely proximate to the forward piecing roll 8, downwardly and rearwardly to a point adjacent the lower part of the doffer cylinder 18, at which point it turns abruptly downward to the girder 11, to 20 which it is attached as indicated in the drawing. The upper part of this front wall is held, removably and adjustably, to the fixed rod 16 by means of a pair of attachment ears 23^a (Fig. 2) bolted to the sliver 25 pan brackets 15, and the junction with the piecing roll 8 is effected by means of a strip of felt 23 secured to the upper edge of the wall. By adjustment of the attachment ears to the pan brackets, this strip can be 30 brought into substantial contact with the piecing roll to close the gap that would otherwise exist at this point, according to the principle explained in Patent No. 864,197. A wedge-shaped filler 24' is secured to the rear or inner face of the front wall 22 to occupy the space between the comb cylinder and the rotary brush, although obviously the wall itself could be bent to conform to this space if preferred, 40 in which case the filler piece would not be necessary.

The front wall 22 is equipped with end wall sections 24 permanently fixed by soldering or otherwise to its opposite upright edges, and the horizontal dimensions of the wall is sufficient to bring such end walls into the space between the comb and brush cylinders and the frame uprights and sufficiently close to the latter to accommodate 50 the usual traverse of the rotary brush. These end sections are cut out to fit or accommodate the comb shaft 6 and the brush shaft 17, the former by means of semi-circular notches 25, and the latter by means 55 of wider notches 26, so formed and related to the machine centers as to permit the said front wall to be slipped into the position indicated in the drawings or removed therefrom without removing any of the operating comber parts. The end wall sections 24, thus constitute about half of the closure at the ends of the comb cylinder and brush. The other half or part is constituted by the supplementary end sections 27 which are 65 held in place by secure attachment to the

machine frame, similarly to the front portion as already described. These supplementary end sections 27, as shown in Fig. 2, are cut with semi-circular notches 28, complementary to the notches 25, and therewith 70 provide a circular opening for the comb cylinder shaft 6, which fits it fairly snugly. They are also cut with notches 29 to accommodate the brush shaft 17, but not so snugly, and the said sections are held in the same 75 planes as the end walls 24 and so as to form close joints therewith by means of the edge-groove or crevice formed by the semi-circular plate or sheet 30 surrounding the notch 25 of the front section, and also by means 80 of a similar seat formed by the clip members 31 soldered to the said front section, just in rear of the brush shaft. The supplementary sections 27 are set in these seats and then secured to the bracket arms 32, which depend 85 from the spring brackets 12 above described, and by means of which the said sections become rigidly mounted in place, and with the front sections constitute the barrier above alluded to. Obviously the clip seats 90 can be formed on either section of the end wall. It is possible to size the notches 25 and 28 to fit the comb cylinder shaft with sufficient closeness to exclude any objectionable inflow of air at this point, but for convenience of assembly the brush shaft notches require to be large and the intervening gap is bridged and closed by a packing in the form of a leather washer 33. This washer is split as shown, so that it can be slipped 100 over the brush shaft, (in the present case outside of the casing) and then be clamped to the casing around the brush shaft as shown in Fig. 2. For this purpose the clamp ring 34 is also split, being made of 105 heavy spring wire as indicated, and secured by a screw or bolt 35 to the end wall section 27 as shown more clearly in Fig. 3. This style of split packing is preferred and constitutes part of the invention, but obviously 110 other means of establishing a substantially complete obstruction to air flow may also be resorted to.

Each supplemental end wall 27 is provided with a marginal shelf rail formed by 115 a narrow strip of metal 36 soldered to its inner face and forming the support for the removable rear wall or cover of the casing. This rear wall is formed of two sections 37 and 38. The former is curved substantially 120 concentric to the comb cylinder and provided with bolts 39 whereby it may be locked to bolt-holes in the end walls 27, and also with a handle 40 whereby it may be conveniently lifted and removed when unlocked. The other section 38 is supplied 125 with similar bolts 39 and handle 40, and, when in normal position meets the upper section 37 with a close joint situated within the V-shaped space between the comb cyl- 130

inder and the brush. The sectional end and rear walls of the casing extend rearwardly over the ends and upper side of the doffer cylinder 18 and around the upper part of 5 the shaft of the latter cylinder, and thus there is formed a substantially perfect inclosure for those parts of the comber which are between the detaching and piecing mechanism at the top and the doffing cylinder at the bottom. The obstruction to air ingress adjacent the shaft journals by the sectional end walls, is supplemented by the substantial closure of the rest of the casing. The closely assembled rolls and nipper jaws 10 constitute obstruction to upward flow, and the doffer cylinder constitutes at least a partial obstruction to downward flow, so that while the air within the casing may be agitated by the rotation of the cylinder and brush, there is no circulation from or to it, with the effect that the air about the journals and other lubricated parts is maintained relatively quiescent and the greatest 15 part of the fluff and fly is retained in the casing and either restored to the lap or discharged in the waste receptacle represented by dotted lines in Fig. 1. The largest opening from the casing is at the bottom beneath the doffing cylinder so that any outward air 20 flow will be directed to the waste receptacle rather than upward through the detaching and piecing rolls, although the deposit of some of the fly on the lap is not objectionable if it is clean.

25 As shown more plainly in Fig. 1, the upper section 37 of the rear wall, when in place is substantially in contact with the under side of the lower nipper jaw, or at least very close to it. The shelf-rail 36 extends beyond the upper edge of the section 37, and also beyond the joint between the end wall sections, where it abuts with a continuing rail or flange 36^a secured to the front end section 24. This extended rail 30 serves as a guard and further closure at the upper part of the casings, at the end of the comb cylinder and shields the journals of the detaching and piecing rolls and adjacent parts from fly that might emerge at 35 that point. The shelf at other points serves to prevent escape of air and fly at the junction between rear walls and end walls, as will be obvious.

40 I am of course aware that cotton combers have heretofore been equipped with the covers or casings for covering the scavenger brush and doffer, but in no instance of which I am aware has any such cover served to prevent air currents over the lubricated journal parts and thereby eliminate the necessity of frequent cleansing and the consequent delay, and I believe myself to be the first to have discovered that by such means as I have above described, the now 45 common idle periods in the operation of

combers can be reduced or avoided, and therefore it is to be understood that, except as specified in the following claims, there is no limitation to any particular form or detail of structure.

70 I claim:

1. In a comber of the kind described, the combination with the comb cylinder, doffer brush and doffing cylinder, of a casing therefor comprising front and rear walls and sectional end walls, the latter being fitted around the comb and brush shafts, and serving to obstruct air flow over the journal portions of such shafts.

75 2. In a cotton comber, the combination with the comb cylinder, rotary brush and doffer cylinder, of a casing comprising a fixed front wall having end wall sections permanently affixed thereto and shaped to accommodate the comb and brush shafts, and supplementary end wall sections engaging said first mentioned end walls from the opposite sides of said shafts.

80 3. In a cotton comber, the combination with the comb, brush and doffer cylinders, of an inclosure therefor comprising a fixed front wall having end wall sections permanently affixed thereto and shaped to accommodate the comb and brush shafts, and complementary end wall sections, rigidly 85 fixed to the frame of the comber.

90 4. In a cotton comber, the combination with the comb cylinder, rotary brush and doffer cylinder, of a casing inclosing the cylinder and brush, having end wall sections provided with seats on the edges thereof, complementary sections seated in said seats, and a removable rear wall.

95 5. In a comber, the combination with the comb cylinder, doffer brush and doffing cylinder, of a casing therefor comprising front and rear walls and end walls, the latter embracing the comb and brush shafts, and closing in the ends of the comb cylinder and brush, and a packing applied to said end 100 walls around one of said shafts.

105 6. In a comber, the combination with the comb cylinder, rotary brush and doffer cylinder, of a casing inclosing said parts at their sides and ends, the end walls being 110 sectional and embracing the brush shaft, and a split packing clamped to the end walls and around said shaft.

115 7. In a cotton comber comprising piecing rolls, comb cylinder, rotary brush and doffer cylinder, the combination of a sectional casing for said cylinder and brush provided with means for shutting off ingress of air thereto at the ends and comprising a split packing and a split packing 120 ring, overlying the junction between sections.

125 8. In a cotton comber, the combination with the piecing rolls, comb cylinder, rotary brush and doffer cylinder, of a casing 130

inclosing the ends and sides of the comb cylinder and brush and comprising a front wall extending from the piecing rolls to a point adjacent the lower end of the doffer cylinder, end walls provided with shelf-bearings and rear walls removably seated on said bearings.

9. In a comber, the combination with the comb cylinder, rotary brush and doffer cylinder, of a casing comprising fixed end walls and a rear wall formed in two sections, provided with independent means for securing them to the end walls.

10. In a comber, the combination of a casing for the comb cylinder and rotary brush, comprising end sections closing the ends of said cylinder and brush and a re-

movable wall and means for bolting the latter to the casing.

11. In a comber, the combination with 20 the piecing rolls, and the comb, brush and doffer cylinders, of a casing or inclosure for said cylinders adapted to confine the lint and fly, and a guard device extending beneath the journals of the said piecing 25 rolls.

In testimony whereof I have signed this specification in the presence of two witnesses.

FRANK L. CROCKETT.
